CLAIM

The ornamental design for the fitting for stone roofs for removing and preventing moss, as shown and described.

DESCRIPTION

FIG. 1 is a perspective view of a fitting for stone roofs for removing and preventing moss showing my new design;
FIG. 2 is a front end view thereof;
FIG. 3 is rear end view thereof;
FIG. 4 is a right side view thereof;
FIG. 5 is a left side view thereof;
FIG. 6 is a top elevation view thereof; and,
FIG. 7 is a bottom elevation view thereof.
